US00D705777S

(12) **United States Design Patent**
Groene et al.

(10) **Patent No.:** **US D705,777 S**
(45) **Date of Patent:** ** *May 27, 2014

(54) **ELECTRONIC TABLET**

(71) Applicant: **Microsoft Corporation**, Redmond, WA (US)

(72) Inventors: **Ralf Groene**, Kirkland, WA (US); **Hua Wang**, Sammamish, WA (US); **Anthony Reed**, Sammamish, WA (US); **Katherine Bailey**, Seattle, WA (US); **James Alec Ishihara**, Bellevue, WA (US); **Jan Raken**, Seattle, WA (US)

(73) Assignee: **Microsoft Corporation**, Redmond, WA (US)

(*) Notice: This patent is subject to a terminal disclaimer.

(**) Term: **14 Years**

(21) Appl. No.: **29/448,262**

(22) Filed: **Mar. 11, 2013**

Related U.S. Application Data

(63) Continuation of application No. 29/422,117, filed on May 16, 2012, now Pat. No. Des. 677,660.

(57) **CLAIM**

The ornamental design for an electronic tablet, as shown and described.

DESCRIPTION

FIG. 1 is a front isometric view of an electronic tablet showing our new design;

FIG. 2 is a rear isometric view thereof;

FIG. 3 is a front view thereof;

FIG. 4 is a top view thereof;

FIG. 5 is a bottom view thereof;

FIG. 6 is a left side view thereof;

FIG. 7 is a right side view thereof; and,

FIG. 8 is a rear view thereof.

The broken line showing of various features on the electronic tablet is for environmental purposes only and forms no part of the claimed design.

1 Claim, 5 Drawing Sheets
